OSCILLATING TOY

Norman E. Dawson, Shalalth, British Columbia, Canada, assignor to H. Fishlove & Co., Chicago, Ill., a corporation of Illinois

Application June 1, 1954, Serial No. 433,553

4 Claims. (Cl. 46—131)

This invention relates to an oscillating toy adapted to simulate the actions of a fisherman.

One of the objects of this invention is to provide a toy comprising a toy figure which is adapted to stand on a supporting surface and which supports a simulated pole and fishing line with a fish or other object attached and so counterweighted that the toy figure will be caused to oscillate on the supporting surface simulating the actions of a fisherman.

Another object is to provide an oscillating toy which by virtue of proper counterbalancing will oscillate for long periods of time, thereby providing a mystery action and affording play value and entertainment for the child.

Another object of this invention is to provide an action toy which is simple and inexpensive to manufacture and which has no moving parts which may get out of order.

Other objects will become apparent as this description progresses.

In the drawings:

Figure 1 is a side view of my toy and showing in dotted lines the oscillating position of same.

Figure 2 is a rear view of the toy figure, and

Figure 3 is a front view of the toy figure.

The toy figure generally indicated at 10 illustrates a figure in standing position tilted rearwardly with the hands in raised position and joined forwardly of the face as shown at 12. The feet or shoes of the figure are rounded as at 14 adjacent the heel to provide a bearing surface on which the figure is supported for oscillation to be described.

Secured or anchored to the body of the toy figure at about the waist portion as indicated at 16 is a simulated pole 18 made of rigid wire which extends vertically upward and passes through the hands as at 19 as though grasped thereby. The pole extends above the hands and body of the figure and is curved forwardly and downwardly as indicated at 22.

Soldered or otherwise secured to the downwardly extending portion of the pole as at 24 is a simulated fishing line generally indicated at 26 which is formed of a spring wire material preferably a piano wire which is formed in an arcuate shape as shown and which tends to retain its shape. The lower end of the wire is suitably anchored as at 28 to a simulated fish generally indicated at 30. Instead of anchoring the wire as shown in the mouth of the fish, a transverse opening may be provided in the head of the fish and the fish may be secured by bending the end of the wire and passing same through said opening and suitably turning or anchoring the end of the wire to prevent disengagement of the fish from the wire. This latter connection provides an additional pivoting action between the fish and wire.

In order to provide the proper oscillation, the weight of the parts above and below the supporting surface are substantially equal. In non-oscillating position, the fish is positioned substantially directly below the toy figure.

The toy figure is supported on any suitable supporting surface or shelf 32 as indicated in Fig. 1 with the fish

2

suspended in the air below and balancing the toy figure. The toy figure thus rests on the heel portions 14 of the feet and the toy body is tilted rearwardly at an inclined angle. By touching the toy figure slightly it will start to oscillate back and forth on the supporting surface about the heels as a pivot and will correspondingly move the pole, line and fish to simulate the actions of a fisherman in attempting to pull a fish out of the water. The spring wire representing the fishing line will by virtue of the 5 springiness of the wire cause the fish to not only move back and forth but also to bounce or sway slightly up and down as well as sidewise thus increasing the action of the toy.

It will be understood that while I have shown a fish at the end of the line that other figures may be used, for example a mermaid or some other appropriate figure.

It will be understood that various changes and modifications may be made from the foregoing without departing from the spirit and scope of the appended claims.

20 I claim:

1. A toy of the class described comprising a toy figure having legs which legs are adapted to rest on a supporting surface for oscillation of said figure, a single simulated pole member formed of rigid material secured to 25 said toy figure and extending upwardly above the top of the toy figure, a single simulated line formed of spring wire material and of arcuate shape secured to said pole and extending forwardly and downwardly of said toy figure and a single simulated fish or like member secured 30 to said simulated line, said single simulated line and single fish or like member serving as the sole counterbalance for said toy figure.

2. An oscillation toy of the character described comprising a toy figure having legs which legs are adapted to 35 rest on a supporting surface for oscillation of said toy, said figure adapted to be tilted rearwardly when in non-oscillating position, a single rigid member secured to said figure and extending vertically upward from said figure, a single arcuate shaped spring wire secured to said single 40 rigid member and extending forwardly and downwardly of said toy figure and a single simulated fish or like member secured to the opposite end of said spring wire so constructed and arranged that said toy figure is maintained in said aforementioned tilted position when in 45 non-oscillating position, said single simulated line and single fish or like member serving as the sole counterbalance for said toy figure.

3. An oscillation toy of the character described comprising a toy figure having legs which legs are adapted to 50 rest on a supporting surface for oscillation of said toy, said figure adapted to be tilted rearwardly when in non-oscillating position, a single rigid member secured to said figure and extending vertically upward from said figure, a single arcuate shaped spring wire secured to said single 55 rigid member and extending forwardly and downwardly of said toy figure, another single toy figure secured to the opposite end of said spring wire and so constructed and arranged that said first toy figure is maintained in said aforementioned tilted position when in non-oscillating position and adapted to tilt forwardly when in an oscillating position, said single arcuate shaped spring wire and said other single toy figure serving as the sole counterbalance for said first toy figure.

4. An oscillation toy of the character described comprising a toy figure in standing position having legs which legs are adapted to rest on a supporting surface for oscillation of said figure, said figure having arms extending forwardly and joined together, said figure adapted to be tilted rearwardly when in non-oscillating position, a single 60 rigid member secured to said figure and extending vertically upward through said arms, a single arcuate shaped spring wire secured to said rigid member and extending 70 vertically upward through said arms, a single arcuate shaped spring wire secured to said rigid member and extending

forwardly and downwardly of said toy figure and a single simulated fish or like member secured to the opposite end of said spring wire so constructed and arranged that said toy figure is maintained in said aforementioned tilted position when in non-oscillating position and adapted to tilt forwardly when in an oscillating position, said single arcuate shaped spring wire and said simulated fish or

like member serving as the sole counterbalance for said toy figure.
